OVEN LIGHT

William Lotter, Cleveland, Ohio, assignor to
American Stove Company, St. Louis, Mo., a cor-
poration of New Jersey

Application February 17, 1941, Serial No. 379,320

19 Claims. (Cl. 240—5)

This invention pertains to an oven and more particularly and specifically to a construction for illuminating the interior of said oven.

The oven is particularly adapted for use in an oven of a cooking range but the inventive concept could be applied to other compartments for the illumination thereof without departing from the inventive concept.

The primary object of the invention is therefore the provision of illumination for the interior of an oven chamber which automatically causes the illumination of the oven upon the opening of the oven door.

A further object of the invention is that of providing in a device of the character hereinbefore described means for manually bringing about the illumination of the oven without the necessity of opening the oven door.

A still further object of the invention is the provision of a device of the character described which is cheap and simple of manufacture and installation yet highly efficient in operation.

Other specific objects, novel features of construction and improved results will appear from the following detailed description when read in the light of the accompanying drawings which illustrate an operative embodiment of the inventive concept.

In the drawings:

Fig. 1 is a vertical sectional view through the oven compartment of any conventional cooking range.

Fig. 2 is a fragmentary horizontal sectional view.

Fig. 3 is a front view of the oven and its door.

In the accompanying drawings an oven chamber A is defined by a front wall 1, a top 2, a rear wall 3 and a bottom which is not shown but is of any well known conventional construction.

At its front the oven is provided with a door B which is provided with a transparent portion (not shown) to permit visual inspection of the interior of the oven chamber even though the oven door be in a closed position.

The door B is hinged so that it is lowered when being opened and moved into a vertical plane when in a closed position.

The exact construction of the hinge for the door is the subject matter of the A. H. Moecker Patent No. 2,179,049 dated November 7, 1939. The door at its lower end is pivotally supported at its opposite sides on the extending hook like ends 43 of the brackets 42 which are rigidly connected to the range at opposite sides of the oven door opening. The hinge includes at each side

10 of the oven door opening an inwardly extending arm or link 4 the outer end of which is pivotally connected to the door as at 4' while its inner end, which always remains in the space between the inner and outer side walls of the oven, is attached as at 5 the lower extending end 6 of a coil spring 7 which has its opposite end 8 anchored to the range front 1. These springs act as a means to partially counterbalance the weight of the door B and as a consequence prevent the door stop 9 from striking the stove front 1 too heavy a blow in the event the door is dropped. It is a fact however that the oven door in many instances is so heavy as to 15 make the spring 7 inadequate to sufficiently cushion the door in the event it is dropped to an open position. This is true by reason of the fact that the hinge and spring are particularly designed for domestic stoves which are of lighter construction rather than for commercial stoves such as heavy duty stoves for use in restaurants, hospitals and similar places.

With the present invention however it is possible to utilize a lighter weight coil counterbalancing spring 7 on a heavy oven door because I have provided for additional counterbalancing or cushioning means. The apparent obvious expediency of enlarging and strengthening the coil spring 7 for taking care of a door of heavier weight would not meet the situation for the reason that these door springs are usually placed within the lining, that is between the inner and outer walls, of an oven and as a consequence the space available for a spring is not sufficiently large to make it possible to utilize heavy springs. Thus, as will presently appear, it is possible to use a standard oven door hinge and counterbalancing spring of medium weight on a range having a door of a greater weight than that for which the counterbalancing spring was designed.

As mentioned, there is at each side of the oven an arm 4 and the now to be described mechanical arrangement is utilized with one or the other of said arms. It is immaterial which of the arms is utilized.

To one of the arms is rigidly attached as at 10 a plate which has an extending portion 11 arranged in separated relationship with an extension portion 12 of the arm to form a clip into which extends an end 13 of an elongated rod 14. The rod end 13 is detachably pivotally connected in its stated position as indicated at 15.

The rod extends practically substantially throughout the depth of the oven chamber and has its rear end 16 extending through a suitable

opening provided in a flange or wall 17 carried by a suitable plate 18 which is welded, bolted, or otherwise suitably secured as at 19 to the side wall 20 of the oven chamber. A coil spring 21 encircles the rod end 16 and is disposed between the wall 17 and a suitable washer or abutment 22 carried by the rod adjacent its end 16.

In the drawings the door is illustrated as being in an open position and it will be obvious that the coil spring 21 is compressed between the wall 17 and the rod abutment 22 and constitutes an auxiliary counterbalancing spring to a portion of the weight of the door and will act to cushion the stoppage of the door in a horizontal plane which is the position that most oven doors assume when in a fully open position.

The rear outermost wall 23 of the range in axial alignment with the rod 14 is provided with an opening 24. Exterior of the range a push-in type of electric switch 25 is mounted upon a suitable bracket 26 and has its actuating button 27 disposed in axial alignment with the rod 14 and as a consequence said push button is exteriorly behind the opening 24 in the rear wall of the range.

This switch is a common form of switch which can be bought on the open market and is spring loaded to hold the push button in an extended position. When the button is in an extended position an electric circuit through the switch is closed and as a consequence the switch can be called a normally closed switch. An inward movement of the button will occur when the oven door is moved to a closed position, as illustrated in dotted lines, as the length of the rod is such that it under these conditions will engage and push the switch push button 27 in and hold it in that position as long as the range oven door is in a closed position. As a consequence as long as the range oven door is closed the switch 25 is open.

A high temperature electric light bulb C is positioned within the oven adjacent the top and rear thereof and is supported in a suitable electric light socket 27 mounted on or in the rear oven wall 23. This socket has an end 28 exterior of the range oven rear wall and to protect the same against damage I provide a suitable guard plate or housing 29. A suitable receptacle or contact block 30 is mounted within a protective box 31 on the rear wall of the oven and has a pair of terminals 32 and 33.

Current for the illumination of the electric light is brought from any suitable source and would in ordinary circumstances be the electric lighting system within the building wherein the range is being used. To obtain current from said source in a conventional manner I provide a pronged plug 34 the two conductors 35 and 36 of which are electrically connected to the receptacle terminals 32 and 33 respectively. One terminal of the electric light socket is connected to the receptacle terminal 32 by a conductor 37.

Inasmuch as it is desirable to provide for illuminated inspection of the oven through the transparent portion of the door when the door is in a closed position I provide means by which the electric circuit to the light can be manually closed rather than closed by the opening of the oven door. To this end I conveniently position, such as on a panel 38 at the front of the range a spring loaded push-in type of switch 39 provided with a push button 40. This switch is normally open but can be closed by an inward pressure upon the push button thereof.

A conductor 41 interconnects the opposite terminal of the light socket to one terminal of the door operated switch 25 while a conductor 42 interconnects the other terminal of this switch to the receptacle terminal 33. A conductor 43 interconnects the receptacle terminal 33 with one terminal 44 of the manually operable push-in switch 39 while the opposite remaining terminal 45 of said switch is connected to the electric light socket terminal 46 by a conductor 47.

It will be understood that the conductors 35, 36, 37, 42 and 43 are always hot. When the oven door is moved to an open position and thus closes the switch 25 the conductor 41 is made hot thus closing the circuit to the electric light through the following conductors, 35, 37, 41 and 42. When the push button 40 is manually operated to bring about illumination of the electric light the circuit is closed to the light through the conductors 35, 37, 47 and 43.

From the foregoing it will be seen that I have provided for either automatic illumination of the oven upon the opening of the oven door or for optional illumination of the oven when the oven door is closed and that this is provided for by an extremely simple cheap arrangement which is simple of manufacture and cheap and simple of installation. Instillation can very readily be made even on ranges now in operation by making the rod 14 of the proper length and suitably attaching it either to the range door hinge or the door of the range whichever proves to be the most convenient. It will further be seen that the rod 14 performs the double function of mechanically actuating and controlling the electric circuit to the electric light and counterbalancing and cushioning the opening movement of the oven door. The springs associated with the door are sufficient to maintain the door at all times in a closed position after the same has been closed and thus assure operative engagement between the rod 14 and the push button 27 of the electric switch 25.

The invention is to be limited only within the scope of the hereinafter appended claims.

I claim:

1. In a cooking range having an oven one wall at least of which is of the double wall type wherein there is an outer and an inner wall in spaced relationship to provide a housing, an electric circuit, an electric light therein, said light being disposed in said oven to illuminate the interior thereof, a switch in said circuit positioned on the exterior side of the rear wall of said oven and biased by resilient means towards a closed position, an oven door opening in the front wall of said oven and a door therefore, said door being supported for swinging movement, a rigid rod within the space between said oven double walls, means pivotally connecting the rod with said door, the rear wall of said oven provided with an opening aligned with said switch, said rod having a rear end adapted to pass through said opening and engage said switch and hold the same in an open position when said oven door is in a closed position, and said rod being moved forwardly toward the front of said oven upon the opening of said oven door to permit said switch to automatically move to a closed position.

2. In a cooking range having an oven one wall at least of which is of the double wall type wherein there is an outer and an inner wall in spaced relationship to provide a housing, an electric circuit, an electric light therein, said light being disposed in said oven to illuminate the

interior thereof, a switch in said circuit positioned on the exterior side of the rear wall of said oven and biased by resilient means towards a closed position, an oven door opening in the front wall of said oven and a door therefor, said door being supported for swinging movement and provided with an arm, said arm extending into the space between said double walls of said oven and having a portion disposed in said space at all times irrespective of the position of said door, a rigid rod within the space between said oven double walls and, means pivotally connecting the rod with said door arm, the rear wall of said oven provided with an opening aligned with said switch, said rod having a rear end adapted to pass through said opening and engage said switch and hold the same in an open position when said oven door is in a closed position, and said rod being moved forwardly toward the front of said oven upon the opening of said oven door to permit said switch to automatically move to a closed position.

3. A construction such as defined in claim 1 wherein, said oven is provided with means which affords inspection of the oven when the oven door is closed, a second electric circuit having connection with said light and having a manually operable switch which is held normally in an open position under resilient tension, and said switch being positioned for convenient manual operation to permit said circuit to be closed and said light illuminated without opening said oven door.

4. A construction such as defined in claim 2 wherein, said oven is provided with means which affords inspection of the oven when the oven door is closed, a second electric circuit having connection with said light and having a manually operable switch which is held normally in an open position under resilient tension, and said switch being positioned for convenient manual operation to permit said circuit to be closed and said light illuminated without opening said oven door.

5. A construction such as defined in claim 1 wherein, resilient means is connected to said door and acts normally to hold said door in a closed position, and resilient means connected to said rod and acting normally to hold said rod in engagement with said switch and functions additionally to counterbalance a portion of the weight of said door as the door is moved into an open position.

6. A construction such as defined in claim 2 wherein, a spring is mounted on the front wall of said oven and disposed wholly within the housing formed by the double wall of said oven, said spring having connection with said door arm and acting normally to hold the door in a closed position, and resilient means connected to said rod and acting to exert a tension thereon to hold said rod in engagement with said switch and to additionally serve to counterbalance a portion of the weight of said door as the door is moved into an open position.

7. In a range, an oven, an oven door hinged at its lower end to the outer oven wall, a link having both ends free of the outer oven wall, an

outer end of said link pivoted to said door and an inner end always disposed within said oven, resilient means arranged between said oven outer wall and the inner end of said link, said resilient means operatively engaging the link and acting to move the door to a closed position, a horizontally disposed rod having an outer end connected to and supported by the said inner end of the link and being movably reciprocated thereby when said door is opened and closed, an electric circuit, and an electric switch therein located in line with the movement of the rear end of said rod and operated thereby to control the flow of current through said circuit.

8. In a range, an oven, a door hinged at its lower edge to said oven, a link located above and apart from said hinge and having an outer end pivoted to said door at a point above and apart from said hinge, said link having an inner end always inside the outer wall of the oven, a switch operating rod having an outer end connected to the inner end of said link and extending inward, an electric switch operative by said rod, an oven light controlled by said switch, and an expanding spring connected with the inner end of said link and the wall of said oven, whereby said link, door and switch rod are movable inward by said spring for the purpose described.

9. In a range, an oven, a door hinged at its lower end to said oven, a link located above and apart from said hinge, the link having an outer end operatively pivotally connected to said door above and apart from said hinge and the inner end of said link being also positioned above and apart from said hinge, a vertically arranged expanding spring having its ends respectively connected with the outer wall of the oven and the inner end of said link, and a horizontally disposed rod within said oven having an outer end pivotally connected with the inner end of said link, and said rod extending rearward, and an electric switch operative by said rod whereby the parts operate as and for the purpose described.

10. In a range or the like, an oven having one side wall of the double wall type wherein there is an outer and an inner wall in spaced relationship to provide a housing, an electric circuit, an electric light in said circuit, said light being disposed to illuminate the interior of the oven, a switch in said circuit positioned on the rear wall of said oven and biased towards a closed position, an oven door opening in the front wall of said oven and a door therefor supported for swinging movement provided with an arm extending into said housing between said oven walls, a rod disposed wholly within said housing and being connected to said door arm, said rod when said door is closed engaging and holding said electric switch in an open position, and said rod when said door is opened being moved forwardly and disengaging said switch to permit the switch to automatically move to a closed position to close said circuit and cause the illumination of said light.

WILLIAM LOTTER.
